(57) **ABSTRACT**

A connector housing includes: a housing body configured to accommodate a connector terminal; and a lever axially supported on the housing body so as to be rotatable around a rotation axis, the lever being configured to rotate around the rotation axis from a temporary lock position to a final lock position to finally lock a mating connector to the housing body by pulling the mating connector having been temporarily locked. The lever includes an operation portion and an arm portion having a shaft-receiving hole. The housing body includes an inner housing formed in a tubular shape that includes a terminal accommodation chamber and having a shaft projection and an outer housing attached to the inner housing such that the arm portion is sandwiched between the outer housing and at least a surface portion of the outer peripheral surface of the inner housing from which the shaft projection projects.

LEVER TYPE ELECTRICAL CONNECTOR WITH INNER AND OUTER HOUSINGS

TECHNICAL FIELD

The present invention relates to a connector housing, a connector in which connector terminals are accommodated in a connector housing, and a wire harness having a connector at an end portion.

BACKGROUND

Japanese Patent Application Publication No. 2003-249303, Japanese Patent Application Publication No. 2003-249304, and Japanese Patent Application Publication No. 2003-249305 disclose conventional connector housings including a lever for assisting connection of connectors. In a connector in which connector terminals are accommodated in such a connector housing, first, a mating connector is temporarily locked to a housing body to which a lever is attached. Thereafter, the lever is rotated to pull the mating connector to make a final locking, so that connection of the connectors is completed. Furthermore, in the above connector housing, an arm portion provided with a shaft-receiving hole is accommodated in an accommodation recess, in a narrow groove-shape, of the housing body, and in the housing body, a shaft projection is fitted into and axially supported by the shaft-receiving hole. The walls of the accommodation recess that sandwich the arm portion from above and below achieve the function of, e.g., preventing the lever from detaching from the housing body.

SUMMARY OF THE INVENTION

Problem to be Solved by the Invention

In this case, when the connector housing is assembled, a lever attachment operation is performed to fit the shaft projection into the shaft-receiving hole while the arm portion is accommodated in the accommodation recess. In this lever attachment operation, the walls of the accommodation recess, which achieve the function of preventing the lever from detaching by sandwiching the arm portion after the attachment, become obstacles to the operation of attaching the lever. For this reason, in the lever attachment operation, it is necessary to, e.g., temporarily widen the groove width by bending the walls of the accommodation recess, i.e., the obstacles. Such an operation not only imposes a burden on the worker, but also may deteriorate the walls of the accommodation recess due to forcible bending and reduce the holding strength of the lever.

Therefore, in view of the above problems, it is an object of the present invention to provide a connector housing, a connector, and a wire harness that reduce the workload related to attachment of the lever and improve the holding strength of the lever.

Solution to Problem

In order to solve the above problems, a connector housing includes a housing body configured to accommodate a connector terminal; and a lever axially supported on the housing body so as to be rotatable around a rotation axis, the lever being configured to rotate around the rotation axis from a temporary lock position to a final lock position to finally lock a mating connector to the housing body by pulling the mating connector having been temporarily

2

locked, wherein the lever includes: an operation portion with which a rotation operation is performed; and an arm portion extending from the operation portion to cross the rotation axis and having a shaft-receiving hole formed at a position that crosses the rotation axis, wherein the housing body includes: an inner housing formed in a tubular shape that includes a terminal accommodation chamber configured to accommodate the connector terminal, a shaft projection configured to be fitted into the shaft-receiving hole of the arm portion projecting from an outer peripheral surface of the inner housing to cross an axis of the tubular shape and form the rotation axis, and an outer housing attached to the inner housing such that the arm portion having the shaft projection being fitted into the shaft-receiving hole is sandwiched between the outer housing and at least a surface portion of the outer peripheral surface from which the shaft projection projects so that the arm portion is rotatable around the rotation axis.

Furthermore, in order to solve the above problems, a connector includes a connector terminal; and the above-described connector housing configured to accommodate the connector terminal.

Furthermore, in order to solve the above problems, a wire harness includes a terminal-attached electric wire having a connector terminal connected to an end portion of an electric wire; and the above-described connector housing configured to accommodate the connector terminal of the terminal-attached electric wire.

Advantageous Effect of the Invention

According to the connector housing, the connector, and the wire harness explained above, the workload related to attachment of the lever can be reduced, and the holding strength of the lever can be improved.

BRIEF DESCRIPTION OF THE DRAWINGS

FIGS. 1A and 1B are perspective views illustrating one embodiment of a wire harness in which FIG. 1A shows the temporary locked position and FIG. 1B shows the final locked position.

FIG. 2 is a perspective view of a connector and a connector housing illustrated in FIGS. 1A and 1B, as viewed from the direction of arrow V11 in FIG. 1B.

FIG. 3A is a cross-sectional view illustrating, as a cross-section taken along line V12-V12 in FIG. 1A, the connector and the connector housing illustrated in FIGS. 1A and 1B and FIG. 2 and

FIG. 3B is an exploded view of a portion of FIG. 3A.

FIG. 4 is an exploded perspective view of the connector and the connector housing illustrated in FIGS. 1 to 3.

FIG. 5 is a schematic view illustrating, as a perspective view, an operation of attaching the lever illustrated in FIG. 4 to the inner housing.

FIG. 6 is a schematic view illustrating, as a perspective view, an operation of attaching the outer housing to the inner housing.

FIG. 7 is a schematic diagram illustrating, as a cross-sectional view taken through the shaft projection, operations from attaching of the lever to attaching of the outer housing.

FIG. 8 is a cross-sectional view illustrating a housing body in a connector housing according to a comparative example with respect to the embodiment illustrated in FIGS. 1 to 7.

FIG. 9 is a drawing schematically illustrating, as a cross-sectional view, attaching of the lever to the connector housing illustrated in FIG. 8.

DETAILED DESCRIPTION OF THE EXEMPLARY EMBODIMENT

Hereinafter, an embodiment of a connector housing, a connector, and a wire harness is described.

FIGS. 1A and 1B are perspective view illustrating an embodiment of a wire harness W1.

The wire harness W1 according to the present embodiment is provided with a connector C1 at an end portion. The connector C1 includes a lever 12 for assisting connection with a mating connector. This lever 12 is operated by a worker, and the lever 12 accordingly rotates from a temporary lock position P11 to a final lock position P12 in a rotation direction D11 around a predetermined rotation axis 12a, thereby assisting the connection between the connector C1 and the mating connector. The temporary lock position P11 is a lever position where the lever 12 is connected to the mating connector when the mating connector is shallowly temporarily locked to the connector C1 in a connector lock direction D12. The final lock position P12 is a lever position where the mating connector, which is temporarily locked and connected to the lever 12, is pulled and finally locked to the connector C1. When the lever 12 rotates to the final lock position P12 and the mating connector is finally locked, the wire harness W1 is electrically connected to the mating wire harness, the mating device, and the like via the connector C1 and the mating connector. Conversely, to disconnect this electrical connection, first, the lever 12 is moved from the final lock position P12 to the temporary lock position P11. This movement releases the final lock between the connector C1 and the mating connector, and returns the connector C1 to the temporary lock state with the mating connector. Thereafter, the worker pulls out the connector C1 from the mating connector. The detailed configuration of the connector C1 in the wire harness W1 and the connector housing 1 that constitutes the connector C1 is described below.

FIG. 2 is a perspective view of a connector and a connector housing illustrated in FIG. 1, as viewed from the direction of arrow V11 in FIG. 1. FIG. 3 is a cross-sectional view illustrating, as a cross-section taken along line V12-V12 in FIG. 1, the connector and the connector housing illustrated in FIGS. 1 and 2. FIG. 4 is an exploded perspective view of the connector and the connector housing illustrated in FIGS. 1 to 3.

The connector C1 includes a connector terminal W111 for each of multiple terminal-attached electric wires W11, a large-sized terminal W121 for each of multiple large-sized terminal-attached electric wires W12, and a connector housing 1. The terminal-attached electric wire W11 has the connector terminal W111 connected to an end portion of an electric wire W112. The large-sized terminal-attached electric wire W12 has the large-sized terminal W121, of which the terminal size is larger than that of the connector terminal W111, connected to an end portion of a large electric wire W122 that is larger than the electric wire W112. In the present embodiment, both of the connector terminals W111 and the large-sized terminals W121 are female-type terminals. The connector housing 1 is a member that accommodates multiple connector terminals W111 and multiple large-sized terminals W121, and includes a housing body 11, a lever 12, and a spacer 13.

The housing body 11 accommodates the multiple connector terminals W111 and the multiple large-sized terminals

W121. The lever 12 is axially supported on the housing body 11 so as to be rotatable around the rotation axis 12a and is configured to rotate from the temporary lock position P11 to the final lock position P12 as illustrated in FIG. 1. The lever 12 finally lock the mating connector to the housing body 11 (and also to the connector C1) by pulling the mating connector having been temporarily locked.

The lever 12 includes: an operation portion 121 with which a rotation operation is performed; and an arm portion 122 extending from the operation portion 121 to cross the rotation axis 12a and having a shaft-receiving hole 122a formed at a position that crosses the rotation axis 12a. In the present embodiment, the lever 12 is formed in a single plate shape constituted by the operation portion 121 and the arm portion 122. The arm portion 122 is formed with a cam groove 122b configured to receive a portion of the mating connector and to move the portion so as to connect or disconnect the mating connector to or from the housing body 11 according to rotation around the rotation axis 12a. When the portion of the mating connector moves inside the cam groove according to rotation of the lever 12 from the temporary lock position P11 to the final lock position P12, the mating connector is pulled toward the housing body 11. Conversely, when the portion of the mating connector moves inside the cam groove according to rotation of the lever 12 from the final lock position P12 to the temporary lock position P11, the mating connector separates from the housing body 11.

The housing body 11 includes an inner housing 111 and an outer housing 112.

The inner housing 111 is a member made of resin formed in a rectangular tubular shape, and includes multiple terminal accommodation chambers 111a accommodating connector terminals W111 and multiple large-sized accommodation chambers 111b accommodating large-sized terminals W121. The terminal accommodation chambers 111a and the large-sized accommodation chambers 111b are provided in the inner housing 111 such that an entry side from which the mating terminal of the mating connector enters is open and an accommodation side in which the connector terminal W111 and the large-sized terminal W121 are accommodated is open. Inside the terminal accommodation chamber 111a, a lance 111a-1 configured to lock with the accommodated connector terminal W111 is provided. Inside the large-sized accommodation chamber 111b, a similar lance is also provided.

An outer peripheral surfaces 111c crossing the rotation axis 12a of outer peripheral surfaces 111c on four sides of the rectangular tubular shape of the inner housing 111 is provided with a shaft projection 111e in a protruding manner. The shaft projection 111e is fitted into the shaft-receiving hole 122a of the arm portion 122. The shaft projection 111e crosses an axis 111d of the inner housing 111 in the tubular shape to form the rotation axis 12a. A lock claw 111f configured to lock with the outer housing 112 is provided on each of the outer peripheral surfaces 111c on the four sides of the inner housing 111.

The outer housing 112 is a cover member made of resin that is attached to the inner housing 111. The arm portion 122 of the lever 12 with the shaft projection 111e being fitted into the shaft-receiving hole 122a is sandwiched between the outer housing 112 and a surface portion 111c-1 of the inner housing 111 from which the shaft projection 111e is projecting, such that the arm portion 122 is rotatable around the rotation axis 12a. The outer housing 112 includes a mask wall portion 112a and an outer tubular portion 112b.

The mask wall portion 112a is a wall portion that covers a contact surface 111g of the inner housing 111, through which the terminal accommodation chambers 111a and the large-sized accommodation chambers 111b are open and which is configured to contact with the mating connector. As illustrated in the enlarged view of FIG. 3, this mask wall portion 112a is provided with through holes 112a-1 and guiding-recessed portions 112a-2 for the mating terminals at positions corresponding to respective openings 111a-2 of the terminal accommodation chambers 111a. The through holes 112a-1 are through holes that are in communication with the openings 111a-2 of the terminal accommodation chambers 111a. The guiding-recessed portions 112a-2 are shape portions for guiding the mating terminals to the through holes 112a-1. The guiding-recessed portions 112a-2 are entrances in a rectangular funnel shape, which are formed around the through holes 112a-1 and of which bottom sides are connected to the through holes 112a-1. Furthermore, the mask wall portion 112a is formed with inspection windows 112a-3, next to the through holes 112a-1, through which the locks of the lances 111a-1 in the terminal accommodation chambers 111a to the connector terminals W111 are confirmed. The mask wall portion 112a is formed with an exposure window 112a-4 in a rectangular shape, through which the openings of the multiple large-sized accommodation chambers 111b are collectively exposed, at a position corresponding to the multiple large-sized accommodation chambers 111b. For the large-sized accommodation chambers 111b, the locks of the lances in the inside are confirmed through the opening of each large-sized accommodation chamber 111b exposed through the exposure window 112a-4.

The outer tubular portion 112b is a wall portion in a rectangular tubular shape extending from the outer peripheral edges of the mask wall portion 112a so as to cover, from the side of the contact surface 111g, the outer peripheral surfaces 111c on the four sides of the inner housing 111, including the surface portion 111c-1 from which the shaft projection 111e projects. Of the outer tubular portion 112b, an opposite surface portion 112b-1 opposite to the surface portion 111c-1 extends longer than the other portions to sandwich the arm portion 122 of the lever 12 between the opposite surface portion 112b-1 and the surface portion 111c-1. The outer tubular portion 112b is formed with lock holes 112b-2 for locking with lock claws 111f formed on the outer peripheral surfaces 111c on the four sides of the inner housing 111.

In this case, the arm portion 122 of the lever 12 is provided with a first lever lock portion 122c for holding the lever 12 at the temporary lock position P11 and a second lever lock portion 122d for holding the lever 12 at the final lock position P12.

The first lever lock portion 122c locks with the outer housing 112 so as to limit rotation to the final lock position P12 when the lever 12 is at the temporary lock position P11. The outer tubular portion 112b of the outer housing 112 is provided with a lock-receiving groove 112b-3, with which the first lever lock portion 122c locks as illustrated in FIGS. 1A and 1B at this occasion. The first lever lock portion 122c is a flexibly bendable cantilever with a projection for locking formed at the tip. Locking of the first lever lock portion 122c to the lock-receiving groove 112b-3 when the lever 12 is at the temporary lock position P11 is made by hooking the projection at the tip to the edge of the lock-receiving groove 112b-3. Then, when the mating connector is temporarily locked to the housing body 11, the first lever lock portion 122c is bent by the mating connector, which enables the protrusion at the tip to pass under the edge of the lock-

receiving groove 112b-3, so that the lock is released. In this state, when the lever 12 rotates to the final lock position P12, the first lever lock portion 122c moves such that the protrusion at the tip of the first lever lock portion 122c passes inside the outer tubular portion 112b to reach the window portion 112b-4 through which the first lever lock portion 122c is exposed and becomes unbent.

Furthermore, the protrusion at the tip of the first lever lock portion 122c is formed with a sloped surface that comes into contact with the edge of the window portion 112b-4 when the lever 12 rotates from the final lock position P12 to the temporary lock position P11. With this sloped surface, when the first lever lock portion 122c rotates to the temporary lock position P11, the first lever lock portion 122c bends so that the protrusion passes under the edge of the window portion 112b-4, and continues to move inside the outer tubular portion 112b to reach the lock-receiving groove 112b-3, where the first lever lock portion 122c is exposed and becomes unbent. Of the projection at the tip of the first lever lock portion 122c, a portion that comes into contact with the edge of the lock-receiving groove 112b-3 when the lever 12 rotates to the final lock position P12 is a standing surface substantially orthogonal to the lever 12. With this standing surface, unless unlocked by the temporary lock of the mating connector, the projection at the tip cannot pass under the edge of the lock-receiving groove 112b-3, so that the lock is maintained to hold the lever 12 at the temporary lock position P11.

In contrast, the second lever lock portion 122d for holding the lever 12 at the final lock position P12 has the following configuration. When the lever 12 rotates to the final lock position P12, the lever 12 locks with the mating connector with the mating connector finally locking with the housing body 11, so that rotation of the lever 12 to the temporary lock position P11 is restricted. The second lever lock portion 122d is a flexibly bendable cantilever with a step for locking formed in the middle. Locking of the second lever lock portion 122d to the mating connector when the lever 12 is at the final lock position P12 is made by hooking the step in the middle to a lock-receiving portion provided on the mating connector. This step is formed in a sloped surface on the entry side for the mating connector, and when the mating connector is to be finally locked, this slope bends the second lever lock portion 122d until it reaches the lock-receiving portion of the mating connector. In contrast, on the lock side for the lock-receiving portion of the mating connector, this step is formed in a standing surface substantially orthogonal to the lever 12. This standing surface makes it impossible to pass the lock-receiving portion of the mating connector, so that the lock is maintained, and the lever 12 is held at the final lock position P12. Then, when the worker pushes down the tip portion of the cantilever beam to bend the second lever lock portion 122d, the step in the middle is unhooked from the lock-receiving portion of the mating connector, so that the lock is released.

Next, the spacer 13 provided in the connector housing 1 is explained. As illustrated in the cross-sectional view of FIG. 3, this spacer 13 is a plate-like member that enters the inside of the inner housing 111 of the housing body 11 by crossing the terminal accommodation chambers 111a. The spacer 13 is provided with multiple tightening regulation portions 131, corresponding to the respective terminal accommodation chambers 111a, for tightening the connector terminals W111 so as to restrict movement of the connector terminals W111 in the terminal accommodation chambers 111a. In the large-sized accommodation chambers 111b of the inner housing 111, regulation of movement of the

large-sized terminals **W121** is sufficiently performed by the locks of large lances in the inside. For this reason, the spacer **13** is formed in such a shape as to cross only the terminal accommodation chambers **111a** and enter the inside of the inner housing **111** without crossing the large-sized accommodation chambers **111b**. As illustrated in FIG. 2 and FIG. 3, an entry portion **111h** for the spacer **13** is open on a side of the inner housing **111** opposite to the shaft projection **111e**. In other words, the shaft projection **111e** is provided to protrude from the surface portion **111c-1** of the outer peripheral surface **111c** of the inner housing **111** that is away from the entry portion **111h** for the spacer **13**. The spacer **13** is fitted from the entry portion **111h** of the inner housing **111** to enter the inside of the inner housing **111**.

In this case, entry of the spacer **13** into the inside of the inner housing **111** is performed by two-stage entry as explained below. First, in a first stage before the connector terminals **W111** are accommodated in the terminal accommodation chambers **111a**, the spacer **13** is pushed in and placed at the first position where the connector terminals **W111** are allowed to move in the inside of the terminal accommodation chambers **111a**. In other words, at this first position, the multiple tightening regulation portions **131** of the spacer **13** do not tighten the connector terminals **W111**, so that the connector terminals **W111** are allowed to move. In the first stage, the spacer **13** is in the temporary lock state at this first position. Then, without being restricted in movement by the tightening regulation portions **131**, the connector terminals **W111** are accommodated in the terminal accommodation chambers **111a** of the connector housing **1** in which the spacer **13** is temporarily locked at the first position. When all the connector terminals **W111** have been accommodated, in a second stage, the spacer **13** is pushed into the inside of the inner housing **111** from the first position and advanced to the second position as follows. That is, at this second position, the tightening regulation portions **131** tightens the connector terminals **W111** to regulate movement of the connector terminals **W111** in the terminal accommodation chambers **111a**. At this second position, the spacer **13** is in the final lock state. The spacer **13** is provided to be movable between the first position and the second position, and when, e.g., the connector terminals **W111** are to be replaced, the spacer **13** is pulled out from the first position to the second position, so that restriction of movement of the connector terminals **W111** is cancelled.

The connector housing **1** as explained above is assembled according to the following procedure. First, the lever **12** is attached to the inner housing **111**, and subsequently, the outer housing **112** is attached to the inner housing **111**.

FIG. 5 is a schematic view illustrating, as a perspective view, an operation of attaching the lever illustrated in FIG. 4 to the inner housing. FIG. 6 is a schematic view illustrating, as a perspective view, an operation of attaching the outer housing to the inner housing. FIG. 7 is a schematic diagram illustrating, as a cross-sectional view taken through the shaft projection, operations from attaching of the lever to attaching of the outer housing.

Attaching of the lever **12** to the inner housing **111** is performed by fitting the shaft projection **111e** of the inner housing **111** into the shaft-receiving hole **122a** of the arm portion **122** of the lever **12**. At this occasion, in the present embodiment, the shaft projection **111e** includes a cylindrical portion **111e-1** having the rotation axis **12a** as a central axis and a lateral branch portion **111e-2** protruding in a lateral branch manner from the circumferential surface of the cylindrical portion **111e-1**. In contrast, the shaft-receiving hole **122a** of the arm portion **122** is formed in a shape in

which a circular hole portion **122a-1** and a fan hole portion **122a-2** are connected. The circular hole portion **122a-1** is a circular hole portion through which the cylindrical portion **111e-1** penetrates in an axial direction **D13** of the rotation axis **12a**. The fan hole portion **122a-2** is a hole portion formed in a fan shape along a trace of a relative movement of the lateral branch portion **111e-2** with respect to the arm portion **122** when the lever **12** rotates between the temporary lock position **P11** and the final lock position **P12** as illustrated in FIGS. 1A and 1B. An interference wall **122a-3** is provided in the inside of the fan hole portion **122a-2**. The interference wall **122a-3** interferes with the lateral branch portion **111e-2** such that the arm portion **122** does not detach from the inner housing **111** in the axial direction **D13** when the lever **12** rotates from the temporary lock position **P11**.

As illustrated in FIG. 5 and FIG. 7, in the first step **S11**, the lever **12** is positioned such that the lateral branch portion **111e-2** of the shaft projection **111e** of the inner housing **111** matches with a penetrating portion of the fan hole portion **122a-2** that does not overlap with the interference wall **122a-3**. In the present embodiment, when the lever **12** is at the temporary lock position **P11**, the lateral branch portion **111e-2** matches with the above-described penetrating portion. In the second step **S12**, the shaft projection **111e** is fitted into the shaft-receiving hole **122a** such that the lateral branch portion **111e-2** passes through the penetrating portion of the fan hole portion **122a-2**. In the second step **S12**, the lever **12** is situated at the temporary lock position **P11**. Thereafter, in step **S13**, the lever **12** is moved in a rotation direction **D11** from the temporary lock position **P11** to the final lock position **P12**. At the final lock position **P12**, the lateral branch portion **111e-2** of the shaft projection **111e** interferes with the interference wall **122a-3** in the inside of the fan hole portion **122a-2**, and the lever **12** is attached to the inner housing **111** in such a detachment-preventing state that the shaft projection **111e** does not detach from the shaft-receiving hole **122a**.

Next, as illustrated in FIG. 6 and FIG. 7, in the fourth step **S14**, the outer housing **112** is positioned such that both the lever **12** in the detachment-preventing state at the final lock position **P12** and the inner housing **111** are in the inside of the outer tubular portion **112b**. In the fifth step **S15**, the outer housing **112** is attached to the inner housing **111**. At this occasion, the lock claws **111f** of the inner housing **111** lock with the lock holes **112b-2** of the outer tubular portion **112b** of the outer housing **112** so that the outer housing **112** locks with the inner housing **111**. As a result, the arm portion **122** of the lever **12** is sandwiched between the surface portion **111c-1** of the inner housing **111**, from which the shaft projection **111e** projects, and the outer tubular portion **112b** of the outer housing **112**. In this state, even if the lever **12** rotates to the temporary lock position **P11**, the outer tubular portion **112b** of the outer housing **112** prevents the lever **12** from detaching. After this fifth step **S15**, the spacer **13** is inserted from the entry portion **111h** of the inner housing **111** so that the connector housing **1** is completed.

Next, a comparative example with respect to the embodiment explained with reference to FIGS. 1A and 1B to FIG. 7 is explained.

FIG. 8 is a cross-sectional view illustrating a housing body in a connector housing according to the comparative example with respect to the embodiment illustrated in FIGS. 1A and 1B to 7. FIG. 9 is a drawing schematically illustrating, as a cross-sectional view, attaching of the lever to the connector housing illustrated in FIG. 8.

In a connector housing **5** according to the comparative example, a housing body **51** is not divided into an inner

housing and an outer housing, and an accommodation recess **51a** in a narrow groove shape for accommodating an arm portion **522** of a lever **52** is formed in the housing body **51**. In this comparative example, a shaft projection **511e**, which is fitted into a shaft-receiving hole **522a** of an arm portion **522**, is provided in the inside of the accommodation recess **51a** of the housing body **51**.

In this comparative example, a wall **51a-1** of the accommodation recess **51a** with which the arm portion **522** is sandwiched in the vertical direction becomes an obstacle against insertion of the arm portion **522**. Therefore, in a first step **S51** of a lever attachment task in this comparative example, the groove width of the accommodation recess **51a** is temporarily widened due to bending of the wall **51a-1** of the accommodation recess **51a**, i.e., the obstacle, in a bending direction **D51**. Thereafter, in a second step **S52**, the arm portion **522** of the lever **52** is inserted in an insertion direction **D52** into the accommodation recess **51a**, of which the groove width is widened, in such a manner as to pass over the shaft projection **511e**. When the arm portion **522** is sufficiently inserted and the shaft projection **511e** is fitted into the shaft-receiving hole **522a**, the wall **51a-1** of the accommodation recess **51a** is unbent.

In this case, in this comparative example, the task of widening the groove width by bending the wall **51a-1** of the accommodation recess **51a** in the first step **S51** tends to be a burden on workers. Furthermore, forcible bending may degrade a base portion **51a-2** that allows for bending of the wall **51a-1** of the accommodation recess **51a**, and may reduce the holding strength of the lever **52**.

In contrast to the comparative example, the connector housing **1**, the connector **C1**, and the wire harness **W1** according to the embodiment explained with reference to FIG. 1 to FIG. 7 can achieve the following effects. Specifically, in the present embodiment, the housing body **11** is divided into the inner housing **111** provided with the shaft projection **111e** for holding the lever and the outer housing **112** attached to the inner housing **111**. This divided configuration enables an attachment task of the lever **12**, including, first, fitting the shaft projection **111e** of the inner housing **111** into the shaft-receiving hole **122a** of the arm portion **122** of the lever **12**, and thereafter, attaching the outer housing **112** so as to cover the arm portion **122**. In this attachment task, the walls sandwiching the lever **12** to prevent the lever **12** from detaching are formed by attaching the outer housing **112** after the arm portion **122** is attached to the inner housing **111**. Therefore, when the shaft projection **111e** is fitted into the shaft-receiving hole **122a**, any obstacle such as a surrounding wall does not exist, and the workload of the attachment task of the lever **12** can be alleviated. Furthermore, it is not necessary to forcibly bend the walls provided for prevention of detachment of the lever **12**, and degradation of the walls due to attachment task of the lever **12** can be prevented. Therefore, the holding strength of the lever **12** can be improved.

In addition, in the present embodiment, the outer housing **112** includes the mask wall portion **112a** for covering the contact surface **111g**, for the mating connector, of the inner housing **111**. The mask wall portion **112a** is provided with the through holes **112a-1** for the mating terminals and the guiding-recessed portions **112a-2** for the mating terminals. According to this configuration, with the guiding-recessed portions **112a-2** of the mask wall portion **112a**, the outer housing **112** also achieves the function of guiding the mating terminals. Therefore, the size of the connector housing **1** can

be reduced as compared with a configuration in which a member having such a guiding function is attached separately.

Furthermore, in the present embodiment, the outer housing **112** includes the mask wall portion **112a** and the outer tubular portion **112b**. The lock claws **111f** are formed on the outer peripheral surface **111c** of the inner housing **111**, and the lock holes **112b-2** are formed on the outer tubular portion **112b** of the outer housing **112**. According to this configuration, the outer housing **112** is attached to the inner housing **111** from the side of the contact surface **111g** for the mating connector. In contrast, a side of the inner housing **111** opposite to the contact surface **111g** is open, and is therefore can be preferably used as an accommodation side in which the connector terminals **W111** are accommodated in the terminal accommodation chambers **111a**. According to the above configuration, the outer housing **112** can be attached by an easy task, i.e., locking the lock claws **111f** with the lock holes **112b-2**.

Furthermore, in the present embodiment, the inner housing **111** is provided with the large-sized accommodation chamber **111b** for accommodating the large-sized terminals **W121** in addition to the terminal accommodation chambers **111a** such that the large-sized accommodation chambers **111b** are open through the contact surface **111g**. The mask wall portion **112a** is provided with the exposure window **112a-4**, through which the openings of the large-sized accommodation chambers **111b** are exposed. According to this configuration, a connector that has multiple types of terminals with different sizes and can transmit multiple types of electrical signals with different voltage and current levels can be made in a preferable manner. The mask wall portion **112a** is formed such that the openings of the large-sized accommodation chambers **111b**, which are large and are therefore not required to guide the mating terminals, are exposed through the exposure window **112a-4**. As a result, the shape of the outer housing **112** can be simplified to reduce the labor required for processing.

Furthermore, in the present embodiment, the lances **111a-1** for locking with the connector terminals **W111** are provided in the inside of the terminal accommodation chambers **111a**. Also, in the mask wall portion **112a**, the inspection windows **112a-3**, through which the locks of the lances **111a-1** are confirmed, are formed next to the through holes **112a-1**. According to this configuration, the locks of the lances **111a-1** with the connector terminals **W111** can be confirmed through the inspection windows **112a-3** formed in the mask wall portion **112a**. Therefore, the connector **C1** that alleviates, e.g., detachment of the connector terminals **W111** from the terminal accommodation chambers **111a** can be made with a high quality.

Furthermore, in the present embodiment, the lever **12** is formed in a single plate shape constituted by the operation portion **121** and the arm portion **122**, and the inner housing **111** is provided with the single shaft projection **111e**. According to this configuration, only the single lever **12** in the single plate shape is axially supported on the inner housing **111**. Therefore, the thickness of the connector housing **1** can be reduced in the axial direction **D13** of the rotation axis **12a** as compared with, for example, a C-shaped lever having two axially supported arm portions **122**.

Furthermore, in the present embodiment, the spacer **13** that enters the inside of the inner housing **111** of the housing body **11** by crossing the terminal accommodation chambers **111a** to restrict movement of the connector terminals **W111** is provided. Also, the shaft projection **111e** is provided to protrude from the surface portion **111c-1** of the outer periph-

11

eral surface **111c** of the inner housing **111** that is away from the entry portion **111h** for the spacer **13**. According to this configuration, the lever **12** in the single plate shape can be attached to the inner housing **111** in a preferable manner, without interfering with the spacer **13** for restricting movement of the connector terminals **W111** in the inside of the terminal accommodation chambers **111a**.

Furthermore, in the present embodiment, the shaft projection **111e** includes the cylindrical portion **111e-1** and the lateral branch portion **111e-2**. The shaft-receiving hole **122a** of the arm portion **122** is formed in a shape in which the circular hole portion **122a-1** and the fan hole portion **122a-2** are connected. Also, the interference wall **122a-3** is provided in the inside of the fan hole portion **122a-2**. The interference wall **122a-3** interferes with the lateral branch portion **111e-2** when the lever **12** rotates from the temporary lock position **P11**. According to this configuration, movement of the lever **12** can be regulated in a preferable manner between the temporary lock position **P11** and the final lock position **P12**, and the lever **12** can be attached to the inner housing **111** at the temporary lock position **P11** in a preferable manner. Also, after the attachment, the position of the lever **12** is moved from the temporary lock position **P11** to cause the lateral branch portion **111e-2** to interfere with the interference wall **122a-3**, so that the lever **12** can be prevented from detaching in a preferable manner even before the outer housing **112** is attached.

Furthermore, in the present embodiment, the arm portion **122** is provided with the first lever lock portion **122c** that locks with the outer housing **112** when the lever **12** is at the temporary lock position **P11** and that unlocks by the mating connector. Also, the arm portion **122** is provided with the second lever lock portion **122d** that locks with the mating connector when the lever **12** to the final lock position **P12** and that unlocks when operated. According to this configuration, when, e.g., the connector housing **1** is transported alone as a component, the first lever lock portion **122c** locks with the outer housing **112**, so that the position of the lever **12** can be stabilized at the temporary lock position **P11**. Also, when, e.g., the connector housing **1** is assembled into the wire harness **W1** and connected to the mating connector, the second lever lock portion **122d** locks with the mating connector, so that the position of the lever **12** can be stabilized at the final lock position **P12**.

It should be noted that the embodiment described above merely shows a representative form of the connector housing, the connector, and the wire harness. The connector housing, the connector, and the wire harness are not limited thereto, and can be modified and implemented in various ways.

For example, in the above-described embodiment, the connector **C1** and the wire harness **W1** having the connector housing **1** in the rectangular block shape have been shown as an example of the connector housing, connector, and wire harness. However, the connector housing, the connector, and the wire harness are not limited thereto. For example, the shape of the connector housing may be, for example, a cylindrical block shape or the like, and the shape of the housing may be any shape.

Furthermore, in the above-described embodiment, the connector housing **1**, in which the outer housing **112** has the mask wall portion **112a** that achieves the function of, e.g., guiding the mating terminals, is shown as an example of the connector housing. However, the connector housing is not limited thereto. The outer housing may be in a simple tubular shape that achieves only the detachment prevention function for sandwiching the arm portion of the lever between the

12

inner housing and the outer housing. However, as described above, when the mask wall portion **112a** that achieves the function of, e.g., guiding the mating terminals is provided in the outer housing **112**, the size of the connector housing **1** can be reduced.

Furthermore, in the above-described embodiment, the connector housing **1**, in which the outer housing **112** formed with the lock holes **112b-2** is attached, from the side of the contact surface **111g**, to the inner housing **111** formed with the lock claws **111f**, is shown as an example of the connector housing. However, the connector housing is not limited thereto, and the structure for attaching the outer housing to the inner housing is not particularly limited. However, as described above, according to the above-described structure of attachment using the lock claws **111f** and the lock holes **112b-2**, the connector terminals **W111** are accommodated in a preferable manner, and the outer housing **112** can be attached by an easy task. Even when a structure for attaching using lock claws and lock holes is provided, the inner housing may be formed with lock holes and the outer housing may be formed with lock claws, conversely to the above-described embodiment.

Furthermore, in the above-described embodiment, the connector housing **1** with the mask wall portion **112a** formed with the exposure window **112a-4** through which the openings of the large-sized accommodation chambers **111b** of the inner housing **111** are exposed is shown as an example of the connector housing. However, the connector housing is not limited thereto. The large-sized accommodation chambers and the exposure window for the openings thereof do not have to be provided, and only small-sized terminal accommodation chambers and through holes and guiding-recessed portions for the openings thereof may be provided. However, as described above, when not only the small-sized terminal accommodation chambers but also the structure corresponding to the large-sized accommodation chambers are provided, the connector that can transmit multiple types of electrical signals can be made in a preferable manner. In addition, as described above, when the exposure window **112a-4** is adopted as the structure of the mask wall portion **112a** corresponding to the large-sized accommodation chambers **111b**, the shape of the outer housing **112** can be simplified to reduce the labor required for processing.

Furthermore, in the above-described embodiment, the connector housing **1**, in which the mask wall portion **112a** of the outer housing **112** is formed with the inspection windows **112a-3** through which the locks of the lances **111a-1** are confirmed, is shown as an example of the connector housing. However, the connector housing is not limited thereto, and such inspection windows do not have to be provided. However, as described above, when the inspection windows **112a-3** for confirming the locks of the lances **111a-1** are provided, the connector **C1** can be made with a high quality.

Furthermore, in the above-described embodiment, the connector housing **1**, in which the inner housing **111** is provided with the single shaft projection **111e** for axially supporting the lever **12** in the single plate shape, is shown as an example of the connector housing. However, the connector housing is not limited thereto. A C-shaped lever having two arm portions may be provided, and the inner housing may be provided with a pair of shaft projections for axially supporting the C-shaped lever. However, as described above, when the structure in which the lever **12** in the single plate shape is axially supported by the single shaft projection **111e** is employed, the thickness of the connector housing **1** can be reduced.

13

Furthermore, in the above-described embodiment, the connector housing 1, in which the spacer 13 is provided to restrict movement of the terminals, and the inner housing 111 is provided with the shaft projection 111e such that the entry portion 111h for the spacer 13 and the lever 12 do not overlap with each other, is shown as an example of the connector housing. However, the connector housing is not limited thereto. The spacer does not have to be provided, and even if the spacer is provided, the shaft projection may be provided such that the lever overlaps with the entry portion. However, as described above, when the shaft projection 111e is provided such that the entry portion 111h of the spacer 13 and the lever 12 do not overlap with each other, the lever 12 in the single plate shape can be attached to the inner housing 111 in a preferable manner.

Furthermore, in the above-described embodiment, the connector housing 1, in which the interference wall 122a-3 that interferes with the lateral branch portion 111e-2 of the shaft projection 111e is provided in the inside of the fan hole portion 122a-2 of the shaft-receiving hole 122a, is shown as an example of the connector housing. However, the connector housing is not limited thereto, and the structure for axial support is not particularly limited. However, as described above, according to the above-described axial structure for causing the lateral branch portion 111e-2 of the shaft projection 111e to interfere with the interference wall 122a-3 of the shaft-receiving hole 122a, the lever 12 can be attached in a preferable manner, and detachment of the lever 12 can be prevented in a preferable manner.

Furthermore, in the above-described embodiment, the connector housing 1 provided with the first lever lock portion 122c for holding the lever 12 at the temporary lock position P11 and the second lever lock portion 122d for holding the lever 12 at the final lock position P12 is shown as an example of the connector housing. However, the connector housing is not limited thereto, and it is not necessary to provide the structure for holding the lever at the temporary lock position and at the final lock position. However, as described above, when the first lever lock portion 122c and the second lever lock portion 122d are provided, the position of the lever 12 can be stabilized at the temporary lock position P11 and the final lock position P12.

	What is claimed is:	
	1. A connector housing comprising:	
	a housing body configured to accommodate a connector terminal; and	
	a lever axially supported on the housing body so as to be rotatable around a rotation axis, the lever being configured to rotate around the rotation axis from a temporary lock position to a final lock position to finally lock a mating connector to the housing body by pulling the mating connector having been temporarily locked, wherein the lever includes:	
	an operation portion with which a rotation operation is performed; and	
	an arm portion extending from the operation portion to cross the rotation axis and having a shaft-receiving hole formed at a position that crosses the rotation axis,	
	wherein the housing body includes:	
	an inner housing formed in a tubular shape that includes a terminal accommodation chamber configured to accommodate the connector terminal, a shaft projection configured to be fitted into the shaft-receiving hole of the arm portion projecting from an outer peripheral surface of the inner housing to cross an axis of the tubular shape and form the rotation axis, and	
	an outer housing attached to the inner housing such that the arm portion having the shaft projection being fitted into the shaft-receiving hole is sandwiched between the outer housing and at least a surface portion of the outer peripheral surface from which the shaft projection projects so that the arm portion is rotatable around the rotation axis.	
	2. A connector comprising:	
	a connector terminal; and	
	the connector housing according to claim 1 configured to accommodate the connector terminal.	

15

3. A wire harness comprising:
a terminal-attached electric wire having a connector terminal connected to an end portion of an electric wire;
and
the connector housing according to claim 1 configured to accommodate the connector terminal of the terminal-attached electric wire.
4. The connector housing according to claim 1, wherein the lever is formed in a single plate shape constituted by the operation portion and the arm portion, and
only one shaft projection is provided on the inner housing.
5. The connector housing according to claim 4, further comprising a spacer that enters an inside of the inner housing of the housing body by crossing the terminal accommodation chamber, the spacer being capable of moving between a first position and a second position, the first position being a position where movement of the connector terminal in the terminal accommodation chamber is allowed, and the second position being a position where the spacer is pressed into the inside of the inner housing from the first position and where movement of the connector terminal in the terminal accommodation chamber is restricted,
wherein the surface portion is a portion of the outer peripheral surface of the inner housing that is away from an entry portion where the spacer enters the inner housing, and the shaft projection is provided to project from the surface portion.
6. The connector housing according to claim 1, wherein the terminal accommodation chamber is provided in the inner housing such that an entry side of the terminal accommodation chamber for a mating terminal of the mating connector is open, and
the outer housing includes a mask wall portion that covers a contact surface of the inner housing for contact with the mating connector, the contact surface being formed with an opening of the terminal accommodation chamber, the mask wall portion being provided with a through hole for the mating terminal and a guiding-recessed portion for guiding the mating terminal to the

16

- through hole, the through hole being formed at a position corresponding to the opening of the terminal accommodation chamber, the guiding-recessed portion being formed around the through hole.
7. The connector housing according to claim 6, wherein the outer housing includes the mask wall portion and an outer tubular portion extending from an outer peripheral edge of the mask wall portion so as to cover, from a side of the contact surface, at least a portion including the surface portion of the outer peripheral surface of the inner housing, and
a lock claw is formed on either one of the outer peripheral surface of the inner housing or the outer tubular portion of the outer housing, and a lock hole with which the lock claw locks is formed on another one of the outer peripheral surface of the inner housing or the outer tubular portion of the outer housing.
8. The connector housing according to claim 6, wherein the housing body furthermore accommodates a large-sized terminal of which terminal size is larger than that of the connector terminal,
the inner housing is provided with a large-sized accommodation chamber for accommodating the large-sized terminal in addition to the terminal accommodation chamber, the contact surface being formed with an opening of the large-sized accommodation chamber, and
the mask wall portion is provided with an exposure window, through which the opening of the large-sized accommodation chamber is exposed.
9. The connector housing according to claim 6, wherein a lance for locking with the connector terminal accommodated in the terminal accommodation chamber is provided in the terminal accommodation chamber, and
the mask wall portion is formed with an inspection window, next to the through hole, through which locking of the lance to the connector terminal is confirmed.
